UNITED STATES PATENT OFFICE.

CHARLES A. COTTAZ, OF NEW YORK, N. Y.

DESIGN FOR A TEXTILE FABRIC.

Application filed October 7, 1927. Serial No. 23,666. Term of patent 3½ years.

To all whom it may concern:

Be it known that I, CHARLES A. COTTAZ, a citizen of the United States of America, and a resident of New York, in the county of New York and State of New York, have invented the new, original, and ornamental Design for Textile Fabric, of which the following is a specification.

Reference is had to the accompanying drawing, of which—

The figure is a face view of a swatch of textile fabric, showing my new design.

I claim:

The ornamental design for textile fabric, substantially as shown.

Signed at New York, in the county of New York and State of New York, this 5th day of October, 1927.

CHARLES A. COTTAZ.
